UNITED STATES PATENT OFFICE.

HENRY PRENZEL, OF PHILADELPHIA, PENNSYLVANIA.

SUPPORTING-INSULATOR FOR TELEGRAPH-WIRES.

SPECIFICATION forming part of Letters Patent No. 315,660, dated April 14, 1885.

Application filed January 21, 1885. (No model.)

To all whom it may concern:

Be it known that I, HENRY PRENZEL, a citizen of the United States, residing at Philadelphia, in the county of Philadelphia and 5 State of Pennsylvania, have invented certain new and useful Improvements in Supporting-Insulators for Telegraph-Wires; and I do hereby declare the following to be a full, clear, and exact description of the invention, 10 such as will enable others skilled in the art to which it appertains to make and use the same.

My invention relates to supporting-insulators for telegraph, telephone, and other electric wires; and the improvement consists 15 in making the insulator in two separable parts, both of which are provided with a central screw-threaded opening, through which is inserted the screw-threaded supporting-peg, the wires being securely held between the upper and lower parts of the insulator, as will be hereinafter shown and described.

In the accompanying drawings, Figure 1 shows an elevation of my improved insulator 25 fitted in position and having two wires passing through and secured therein. Fig. 2 is a cross-section of Fig. 1. Fig. 3 is a plan. Fig. 4 is a cross-section showing a modification of Fig. 1. In this figure the top part of 30 the insulator is made convex and the under or bottom part concave. Fig. 5 is a cross-section showing another modified form in which the top is concave and the bottom part convex.

35 A represents the cross-piece attached to the telegraph-pole.

B is the peg or support to which the insulator is secured.

C is the lower half of the insulator, which 40 is made of glass or any other suitable material. C' is the upper half of the insulator. Both of these parts are provided with a central screw-threaded opening fitting over or upon a corresponding screw-thread formed on the 45 supporting-peg B.

c c are grooves on the upper surface of the lower part of the insulator.

d d are telegraph-wires fitting into the grooves c c.

50 C' is a square projection formed on the top of the upper half, C', for the purpose of fitting a wrench thereto, so that the two parts may be tightly screwed together. C" is a similar square projection on the base of the lower half, C, for a like purpose.

The under surface of the upper half and upper surface of the lower half of the insulator may be made flat, as shown in Figs. 1 and 3; or they may be formed, respectively, with convex and concave surfaces fitting into each other, as shown in Figs. 4 and 5, in which case the grooves c c are made to conform to the shape of the surface of the lower half of the insulator. By this latter means a more secure grip is obtained upon the wire, 65 as the two parts coming together form a circular bend upon the wire corresponding in shape to the grooves.

The lower part, C, of the insulator being fitted to the supporting-peg B, to secure the 70 wire or wires in position, it is only necessary to fit them into the grooves c c, draw them to the required tension, and screw the upper half, C', down toward the lower half, C. As the wires project beyond the grooves 75 c c, they are held firmly between the two parts of the insulator.

It will be readily seen that by the use of an insulator constructed in this way the wires can be easily and quickly adjusted, and at the 80 same time accomplish a saving of the wire ordinarily used in tying the telegraph-line to the insulator.

I am aware that telegraph-insulators have been made in two separable parts connected 85 together by a screw passing through a smooth central opening in each of said parts and screwing into the wooden bracket or the stem holding the insulator, also that insulators have been made with the upper separable part 90 provided with a screw-threaded opening fitting on the supporting-peg. I do not, therefore, claim either of these inventions.

What I do claim, and desire to secure by Letters Patent of the United States, is— 95

In a supporting-insulator for electric wires, the lower half, C, having an internally-screw-threaded opening, and provided with a groove or grooves, c, in combination with the upper half, C', having an internally-screw-threaded 100 opening, and the screw-threaded supporting-peg B, all substantially as and for the purpose described.

In testimony whereof I affix my signature in presence of two witnesses.

HENRY PRENZEL.

Witnesses:

THOMAS D. MOWLDIS,
OTIS EGAN.
